UNITED STATES PATENT OFFICE.

JOSEF GRANZ, OF PLAUE, GERMANY, ASSIGNOR TO VOGTLANDISCHE MASCHINEN-FABRIK, OF PLAUE, GERMANY.

TAMBOUR-FRAME-DRIVING MECHANISM.

Application filed June 4, 1914. Serial No. 842,903.

(GRANTED UNDER THE PROVISIONS OF THE ACT OF MARCH 3, 1921, 41 STAT. L. 1313.)

To all whom it may concern:

Be it known that I, JOSEF GRANZ, subject of the German Emperor, residing at Plauen, in Vogtland, in the Kingdom of Saxony, Germany, have invented certain new and useful Improvements in Tambour-Frame-Driving Mechanism, of which the following is a specification.

The present invention relates to tambour frame driving mechanism. Among the difficulties met in the embroidering machine art is the problem to transmit uniform motion to all points of long tambour frames. Since tambour frames are not absolutely rigid bodies, but to a certain extent flexible, there is a variance in the motion carried out by the different points of the tambour frame. In consequence thereof the embroidery design becomes distorted and the work unsatisfactory.

The solution of the problem is rendered the more difficult the longer the tambour frames are and the more rapid the successive stitches or other operations are performed. The irregularity in the work becomes particularly noticeable when produced on automatic embroidering machines which, in order to compensate for the high cost of manufacture thereof, must be built so as to afford the maximum output which is attained by enlarging the embroidery area or in other words, the tambour frame.

In the hitherto used machines in order to solve the problem, the tambour frame is positively guided at two or more places, while the drive is independent of the guides and is specially arranged.

According to this invention the tambour frame is supported at several points of its length on driven means whereby vertical motion is transmitted thereto and which means act on the frame directly in the plane of the center of gravity thereof and are actuated simultaneously through the medium of counterbalancing means near each end of the frame.

One embodiment of my invention is illustrated in the accompanying drawing, in which similar reference characters denote corresponding parts and in which Fig. 1 shows in a more or less diagrammatic view an automatic embroidering machine and Fig. 2 is a modification of a detail thereof.

Referring to the drawings 1 denotes the jacquard mechanism or automat which as usual controls the movement of the tambour frame 2 through the medium of vertical and horizontal shafts 3, 4, the free ends of which carry or are formed with gears 3', 4'. These gears in well known manner transmit motion to horizontal and vertical slides 5, 6. Supported on the stationary frame 7 of the machine and at each end thereof is a spring counterbalancing mechanism 8 of the kind shown and described in the co-pending application Serial No. 817,497, filed February 9, 1914, patented January 12, 1915, Patent Number 1,124,572, or which may be of any other suitable and well known construction.

At the opposite end of the frame I provide a vertical slide 6'. The two slides 6, 6' each carry a roller 6^a and these rollers are adapted to support the tambour frame in a vertical plane passing through the center of gravity of the tambour frame. Projecting from each end of the stationary frame 7 is an arm 7^a which carries a roller 7^b. Each vertical slide 6, 6' has connected to its upper free end 6^b a metal band 9 which is guided around the respective roller 7^b and which with its other end is directly connected to the respective counterbalancing mechanism 8. The counterbalancing mechanisms are positively connected with one another by crossing metal bands 10. In this manner motion from the driving mechanism is directly and positively transmitted to the two ends of the tambour frame and simultaneously the counterbalancing mechanisms are actuated.

In addition motion is positively transmitted to an intermediate point of the tambour frame located adjacent to or in the vertical line passing through the center of gravity of the tambour frame. To this end a roller 11 is carried by an arm 12 projecting from an intermediate point of the tambour frame. This roller movably engages a horizontal loop 13 provided at the lower end of a vertical slide 14 guided in a bracket 15 fixed to the stationary frame 7. At its upper end the bracket 15 carries a roller 16 which is arranged opposite to and in a vertical plane with the rollers 7^b. A metal band 17 guided around the left roller 7^b is conveyed around the roller 16 and has

one of its ends fixed to the lower part of the slide 14, as at 14^a, and the other end fixed to the upper part of the slide, as at 14^b. This additional mechanism affords the positive transmission of motion from the driving mechanism to an intermediate point of the tambour frame simultaneously with that transmitted to the ends thereof.

Instead of the loop 13 and the roller 11 10 the vertical slide 14 may be provided with two superposed rollers 18, 19 that positively engage between themselves the upper cross bar 2^a of the tambour frames 2, as shown in Fig. 2.

15 What I claim and desire to secure by Letters Patent is:

1. In an embroidering machine, the combination with the tambour frame, of driven means for transmitting vertical motion thereto at several points of the length of and acting on the said frame directly in the vertical plane of the center of gravity thereof and spring counterbalancing means near

each end of the said frame positively connected to each other and through the medium of which the several driven means are actuated simultaneously.

2. In an embroidering machine, the combination with the tambour frame, of driven means for transmitting vertical motion thereto at several points of the length of and acting on the said frame directly in the vertical plane of the center of gravity thereof, counterbalancing means near each end of the said frame and flexible bands positively connecting the said counterbalancing means to each other and to said driven means and whereby the said driven means are actuated simultaneously.

In testimony whereof I affix my signature in presence of two witnesses.

JOSEF GRANZ.
